UNITED STATES PATENT OFFICE.

FRANK L. FURBUSH AND ALLAN C. SARGENT, OF WESTFORD, MASSACHUSETTS, AS-
SIGNORS TO C. G. SARGENT'S SONS CORPORATION, OF GRANITEVILLE, MASSACHU-
SETTS, A CORPORATION OF MASSACHUSETTS.

EXHAUST-AIR CONDUIT FOR DRIERS

Application filed February 25, 1924. Serial No. 694,997.

To all whom it may concern:

Be it known that we, **FRANK L. FURBUSH** and **ALLAN C. SARGENT**, both citizens of the United States, both residing at Westford, 5 in the county of Middlesex and State of Massachusetts, have invented a new and useful Exhaust-Air Conduit for Driers, of which the following is a specification.

which the following is a specification:

This invention relates to a drier for fibrous material of the type in which the material is carried through the main casing of the drier on one or preferably a plurality of aprons so that the material is carried back and forth through it.

15 The principal objects of the invention are to provide a more efficient conduit for taking out the air from the drier and especially to improve the construction of the conduit so that the air will not be robbed from the 20 circulating fans and so that the slot through which the air is introduced into the exhaust conduit can be adjusted to accommodate variations in draft and moisture; and also to provide yielding means for regulating 25 the width of the slot and a construction whereby the stock will not be sucked into the conduit.

Other objects and advantages of the invention will appear hereinafter.

30 Reference is to be had to the accompanying drawings, in which—

Fig. 1 is a vertical sectional view through the drier and conduit showing details of construction of the latter;

35 Fig. 2 is a longitudinal sectional view of the two ends of one wall of the drier conduit on the inclined line 2-2 of Fig. 1;

Fig. 3 is a side elevation; and

Fig. 4 is a plan of the same.

40 We have shown the invention as applied to a well known type of three-apron drier in which the wool, cotton or other fibrous material is taken back and forth through the drying chamber 10 on three endless aprons 11, 12 and 13, one over the other. 45 These aprons are of material of such a nature that the air can pass through them on the way to the exhaust fan 14 at the end of the top of the drier. It is drawn

50 in at the bottom through a chamber 9 provided with heating coils, not shown. It is to be understood, however, that the invention is not limited to any particular number of aprons or to any kind and that the

aprons themselves do not constitute a part of this invention. For that reason they are not described in detail.

In order to draw the air out from the top of the drier all along the same and provide for the advantages above mentioned, we connect the intake of the exhaust fan 14, which is located at one end of the drier, with another conduit 15 located along the top of the casing 10. This conduit is formed mainly by two walls 16 and 17 of sheet metal. The sheet steel wall on one side, that is, the side 16, is longer than the other so as not to rob the circulating fans of air. These two walls are both inclined so that the cross-section of the conduit is 70 triangular, preferably a right triangle. 60

The wall 16, as stated, extends beyond the wall 17 and is spaced from it at the bottom. It is provided with a foot piece 18 extending throughout its length nearly parallel with the wall 17 and extending up to a point at about the lower end thereof and spaced from it. The bottom of the wall 17 has a right angle projection 19 extending toward the foot piece 18 but spaced from it, leaving an inlet slot 20 between them. This slot it will be seen receives air from above and cannot receive it directly from below. This forces the air upwardly from the stock throughout the length of it and then downwardly into this slot 20. This slot is also tapered from end to end, the smaller end being nearest the exhaust fan so that where the draft is strongest the slot 20 will be the narrowest. The whole conduit also tapers in a similar manner, as will be seen from the side view. 90

In order to adjust the slot 20, we provide a series of adjusting bolts 21 extending from the projection 19 through the bottom of the wall 16, each one with a thumb nut 22 on the lower end and springs 23 are provided to yieldingly resist the approach of the wall 16 to the projection 19. Therefore when these nuts are tightened up at all the two walls are held apart yieldingly but firmly and it is a very easy matter to adjust them farther apart or nearer together. 95 100

In the operation of the device the air is drawn in through the chamber 9 to the bottom of the drier and circulates upwardly throughout its length through all the three aprons. It goes upwardly also from the lay- 105

- er of stock on the top apron and then downwardly into the slot 20 throughout the length of the drier. Then it is drawn along the triangular conduit 15 into the exhaust 5 fan 14 through a connection 24 extending into its intake. This insures the circulation of air throughout the length of the drier and its withdrawal from all parts of the upper layer of fibrous material on the top again.
- 10 It permits of the adjustment of the intake slot 20 to any desired degree and avoids the taking of too much air from the circulating fans 28 so that it will all have to pass through the material to be dried.
- 15 Although we have illustrated and described the invention as applied to a particular type of drier for fibrous materials and shown in detail the construction of the apparatus as preferably made, we are aware 20 of the fact that the invention can be applied to other makes of driers and that modifications can be made by any person skilled in the art without departing from the scope of the invention as expressed in the claims.
- 25 Therefore we do not wish to be limited to all the details of construction herein shown and described or to the particular form of drier illustrated but what we do claim is:
1. In a drier for fibrous materials, the combination with a casing having a plurality of 30 endless apron conveyors therein for the stock and located one over the other, and an exhaust fan for drawing the air through the several aprons and out of the drier, of a 35 conduit of triangular shape extending along in the top of said casing over the top apron, said conduit having a slot therein near the bottom but opening upwardly from it.
2. In a drier for fibrous materials, the combination with a casing and an endless apron 40 therein for conveying the material to be dried through the casing, of an exhaust fan for drawing the air over the material and out of the casing, a longitudinal conduit in 45 the top of said casing connected with the fan and having a slot near the bottom for receiving the air from the material on the apron, and means for adjusting the slot to control the current.
- 50 3. In a drier for fibrous materials, the combination with a casing and an endless apron therein for conveying the material to

be dried through the casing, of an exhaust fan for drawing the air over the material and out of the casing, a longitudinal conduit in the top of said casing connected with the fan and having a slot near the bottom for receiving the air from the material on the apron, a series of bolts for connecting the walls of the conduit on opposite sides of 55 said slot, nuts on said bolts for drawing the walls of the conduit toward each other and narrowing the intake slot, and springs on the bolts for holding the walls of the conduit apart yieldingly.

4. The combination with a drier casing and an exhaust fan, of a triangular conduit in the top of the casing extending throughout the length thereof, the bottom of one wall of said conduit extending beyond the lower edge of the other and projecting upwardly at its extreme end to provide a slot throughout the length of the conduit opening downwardly into the conduit for the entrance of air from the stock throughout the length of the casing.

5. The combination with a drier casing and an exhaust fan, of a triangular conduit in the top of the casing extending throughout the length thereof, one wall of said conduit extending beyond the lower end of the other at the bottom and projecting upwardly at its extreme end beyond the other wall to provide a slot throughout the length of the conduit opening downwardly into the conduit for the entrance of air from the stock throughout the length of the casing, said slot tapering from end to end.

6. A conduit for a drier comprising a wall extending substantially throughout the length of the drier at an inclination, a second wall of the same extent inclined in the opposite direction to make the conduit triangular in shape, the second wall extending below and beyond the lower end of the first wall and spaced therefrom, said conduit tapering from one end to the other, the slot between the two walls at the bottom also being tapered in the same direction.

In testimony whereof we have hereunto affixed our signatures.

FRANK L. FURBUSH.
ALLAN C. SARGENT.
